UNITED STATES PATENT OFFICE.

DAVID W. BOWE, OF DETROIT, MICHIGAN.

CLAMP.

1,387,917.

Specification of Letters Patent. Patented Aug. 16, 1921.

Application filed June 3, 1920. Serial No. 386,374.

To all whom it may concern:

Be it known that I, DAVID W. BOWE, a citizen of the United States, residing at Detroit, in the county of Wayne and State 5 of Michigan, have invented a new and useful Clamp, of which the following is a specification.

This invention has reference to hoisting hooks, and more particularly to hoisting 10 hooks especially designed for use in hoisting railway rails or the like.

The primary object of the invention is to provide a hoisting hook which will position itself on the rail under operation, and 15 one which will be automatically locked in such position to insure against the release of the hook.

A further object of the invention is to provide a device of this character wherein the 20 weight of the article being lifted will cause the jaws to move toward each other to securely grip the article, associated therewith.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawings:-

35 Figure 1 illustrates a side elevational view of a clamp showing the same as applied to a rail.

Fig. 2 illustrates a longitudinal sectional view through a clamp, and

40 Fig. 3 illustrates a sectional view taken on line 3—3 of Fig. 2.

Referring to the drawing in detail, the device forming the subject matter of this invention includes opposed jaw sections 5 and 6 respectively, the jaw section 5 being provided with the flanges 7 adapted to embrace the flanges 8 of the opposed jaw section 6.

50 The jaw sections, and more particularly the flanges thereof are provided with openings indicated at 9, which openings, when the jaws are in assembled relation register to accommodate the bolt 10 providing the pivot for the jaws, to permit the jaws to

rock with relation to each other, to accomplish the gripping result.

Formed in each of the jaw sections is a cut out portion indicated at 11, the ends thereof being curved as at 12 to provide camming surfaces, for purposes to be hereinafter more fully described.

The supporting member, forming a part of the clamp comprises the head 13 provided with an elongated opening 14 extending longitudinally of the head, to permit of movement of the supporting member with relation to the jaw sections, the movement of the supporting member being limited by the length of the cut out portion 11.

Curved surfaces 15 are formed on the 70 head 13, while at the opposite end thereof, the curved surfaces 16 are provided, the curved surfaces 15 coöperating with the curved surfaces formed at the upper ends of the jaw sections for rocking the jaw 75 sections to move the clamping ends thereof toward each other, that is when the device is lifting, and the supporting member is moving in one direction. When the supporting member is moved in the opposite direction, the curved portions 16 of the head 13, contact with the curved surfaces 12, disposed adjacent to the lower ends of the jaw sections, to cause the jaw sections to move away from each other, or moved to an open 85 position.

In order that the jaw sections will be automatically locked in their open positions, the spring latch member indicated at 17 is provided, one end of which is secured to one 90 of the sections as by means of the screws 18, the opposite end thereof extending at right angles to position itself in the opening 19, formed in the opposed jaw section, so that the jaws may be permitted to move to a 95 closed position, only after the latch member has been moved to release the jaw sections.

Having thus described the invention, what is claimed as new is:-

In a hoisting hook, a supporting member 100 having a head, formed at one end thereof, said head having an elongated opening formed therein, opposed jaw sections having pivotal connection with the head, said jaw sections having openings registering 105 with the elongated opening in the head, a bolt passing through the opening, for securing the jaw sections to the supporting mem-

ber, said jaw sections having curved surfaces, said head having curved surfaces, the curved surfaces adapted to coöperate to move the free ends of the jaw sections with relation to each other, when the head is moved within the jaw sections, and means for locking the jaw sections in an open position.

In testimony that I claim the foregoing as my own, I have hereto affixed my signature 10 in the presence of two witnesses.

DAVID W. BOWE.
